Attorney

UNITED STATES PATENT OFFICE

PHILIP SINITZER, OF BROOKLYN, NEW YORK

GARMENT HANGER

Application filed March 13, 1929. Serial No. 346,665.

The present invention relates to garment hangers, the main object of the invention being to provide a garment hanger made of the minimum number of parts and capable of manufacture and assembly with the minimum number of operations.

Another object of the invention is to provide a garment hanger with a moth ball carrier which may be readily loaded and 10 unloaded.

The various features of the novelty which characterize my invention are pointed out in the claims annexed hereto and forming a part of this specification. For a clear 15 understanding of my invention reference may be had to the following description taken in connection with the accompanying drawings.

Fig. 1 shows a front elevation of one 20 embodiment of my invention.

Fig. 2 is a similar view with the cover plate shown in section and one of the moth ball containers shown in retracted position for loading and unloading the container.

Fig. 3 shows a detailed view taken on 25 line 3—3 of Fig. 1.

Fig. 4 is a plan view of the cover plate detached from the hanger showing the lugs in expanded position.

Fig. 5 shows a modified embodiment of 30 my invention.

In the preferred embodiment of the invention as shown in Fig. 1 the garment hanger as such consists of only two elements, 35 the construction of each of which is simple, the two elements when assembled together constituting a completed garment hanger for supporting a coat and trousers. One of the elements consists of an integral wire 40 10 which is bent to the shape shown so as to provide a hook 11 at one of its free ends and a looped over portion 12 at the other free end which is adapted to slip over the hook portion 11. The intermediate portions of 45 the integral wire 10 are bent to form a horizontal trouser supporting bar 13 and a pair of shoulder supporting arms 14 and 15. The portion immediately adjacent the outer ends of the shoulder supporting arms 50 14 and 15 are preferably looped in the man-

ner shown in Fig. 3 to provide horizontal supporting loops 16 and 17. The portions disposed between the horizontal trouser supporting bar 13 and the loops 16 and 17 are preferably bent to occupy a vertical 55 position as shown at 18 and 19, these portions serving to space the horizontal trouser supporting bar 13 from the other portions of the hanger.

In order to provide a substantial support 60 ing surface for the shoulders of the coat the cover plate 20, which is preferably stamped out of sheet metal, is carried by the wire, the hook portion of the wire passing through an aperture disposed centrally 65 of the cover plate 20. The cover plate is preferably curved longitudinally and transversely so as to provide a supporting surface for the shoulders of the coat of such a nature that the coat will hang properly 70 thereon.

The ends of the cover plate 20 are provided with integral lugs 21, 22, which are formed in the same stamping operation, these lugs serving to hold the elements of 75 the hanger in properly assembled relation by bending same over the lower face of the loops 16 and 17 respectively.

The construction described hereinabove constitutes an improved garment hanger 80 which is cheap to manufacture and which when in use offers a support for coat and trousers of such a nature that such garments will not be deformed in any manner.

Another feature of the present invention 85 resides in providing a garment hanger with one or more moth ball containers. It is one of the objects of the present invention to construct the moth ball containers in such a manner that they may be loaded and un- 90 loaded with facility and to obviate the accidental loss of such moth balls. For this purpose the preferred embodiment of the invention contains a pair of moth ball containers 23 and 24 carried respectively be- 95 tween shoulder supporting arms 14 and 15. The moth ball containers each consist of an open helical coil of resilient wire, the coils being slipped over the shoulder supporting arms 14 and 15 respectively in such a man- 100

ner that their open ends 25 face each other and constitute closures each for the other. The ends 26 and 27 of the containers are preferably closed so that moth balls cannot 5 pass through such ends, the closure consisting of coils of the same wire as the remainder of the container, these coils however, being disposed in a spiral of diminishing diameter.

10 Fig. 2 illustrates the manner in which these containers may be loaded and unloaded. The operator retracts the desired container with his thumb while holding the hanger in the same hand, the other hand 15 being free to load or unload the container.

10 While the construction shown in Figs. 1 to 4 inclusive and described hereinabove is the preferred embodiment of the invention for the reason that it provides a simple and 20 cheap construction wherein the various elements are assembled without any welding operations, Fig. 5 shows a modified embodiment of the invention. In this form of the invention the cover plate 20 is identical with 25 the corresponding element in Fig. 1. The moth ball container 28 is substantially identical with the containers shown in Fig. 1 except that instead of providing two such containers, only one long container is provided 30 which is also in the form of an open helical coil of resilient wire. The metallic strip or wire 29 serves to hold the container 28 in position, the free ends of the wire 29 being held in place by means of the integral lugs 31, 32, of the cover plate 20. If desired the 35 ends of the helical container 28 may be covered with disks 30 which are provided with resilient lugs 31 cooperating with the end turns of the container 28 to close the same. 40 The hook 32 is welded or otherwise attached to the strip or wire 29 at the point 33. If desired a trouser supporting horizontal bar 34 may be assembled with the hanger, the bar being provided with horizontal portions 45 35, 36, which are held in position by means of the lugs 21, 22.

I claim:

1. A garment hanger comprising; an integral wire bent to form a supporting hook, 50 a pair of shoulder supporting arms, a horizontal trouser support and a horizontally disposed loop at the end of each shoulder arm; a longitudinally and transversely curved cover plate, having a central aperture to receive said hook, and disposed over 55 said shoulder arms, said plate having a stamped integral lug at each end thereof bent over said horizontal loops to hold the elements in proper assembly; and a moth ball container carried by each shoulder arm, said container consisting of an open helical coil of resilient wire; each of said containers 60 having one conical end closure at the outer end of said shoulder arms, the open ends of 65 said coils being disposed adjacent each other

and serving as closures each for the other, whereby either container may be compressed at its open end to provide access to the interior thereof.

2. A garment hanger comprising: an integral wire bent to form a supporting hook, 70 a pair of shoulder supporting arms, a horizontal trouser support and a horizontally disposed loop at the end of each shoulder arm; a cover plate, having a central aperture to receive said hook, and disposed over 75 said shoulder arms, said plate having a stamped integral lug at each end thereof bent over said horizontal loops to hold the elements in proper assembly; and a moth ball container carried by each shoulder arm, said container consisting of an open helical coil of resilient wire; each of said containers 80 having one conical end closure at the outer end of said shoulder arms, the open ends of 85 said coils facing each other and serving as closures each for the other, whereby either container may be compressed at its open end to provide access to the interior thereof.

3. A garment hanger comprising: an integral wire bent to form a supporting hook, 90 a pair of shoulder supporting arms, a horizontal trouser support and a horizontally disposed loop at the end of each shoulder arm: a cover plate disposed over said shoulder arms, said plate having a stamped integral lug at each end thereof bent over 95 said horizontal loops to hold the elements in proper assembly; and a moth ball container carried by each shoulder arm, said container consisting of an open helical coil of resilient wire; each of said containers having one conical end closure at the outer end of 100 said shoulder arms, the open ends of said coils facing each other and serving as closures each for the other, whereby either container may be compressed at its open end to provide access to the interior thereof.

4. A garment hanger comprising: an integral wire bent to form a supporting hook, 110 a pair of shoulder supporting arms, and a horizontal trouser support and a horizontally disposed loop at the end of each shoulder arm; a cover plate carried by said wire and disposed over said shoulder arms, said plate 115 having means cooperating with the ends of said shoulder arms to hold the elements in proper assembly, and a moth ball container carried by each shoulder arm, said containers consisting of an open helical coil of 120 resilient wire, each of said containers having one conical end closure at the outer end of said shoulder arms, the open ends of said coils facing each other and serving as closures each for the other, whereby either container may be compressed at its open end to provide access to the interior thereof.

5. A garment hanger comprising: an integral wire bent to form a supporting hook, 125 a pair of shoulder supporting arms, a hori- 130

- 5 zontal trouser support and a horizontally disposed loop at the end of each shoulder arm; and a longitudinally and transversely curved cover plate, having a central aperture to receive said hook and disposed over said shoulder arms, said plate having a stamped integral lug at each end thereof bent over said horizontal loops to hold the elements in proper assembly.

10 6. A garment hanger comprising: an integral wire bent to form a supporting hook, a pair of shoulder supporting arms, a horizontal trouser support and a loop at the end of each shoulder arm; a longitudinally and transversely curved cover plate disposed over said shoulder arms, said plate having a stamped integral lug at each end thereof bent over said loops to hold the elements in proper assembly, and a moth ball container carried by each shoulder arm, said containers consisting of an open helical coil of resilient wire.

15 7. A garment hanger comprising: an integral wire having one end formed into a supporting hook, the other end constituting a shoulder supporting arm having its free end formed into a loop to be slipped over said hook, the portion adjacent said hook constituting another shoulder supporting arm, the portion between said arms constituting a horizontal trouser support; and a moth ball container carried by each shoulder arm, said container consisting of an open helical coil of resilient wire, and a conical end closure at one end consisting of coils of the same wire disposed in a spiral of diminishing diameter.

20 8. A garment hanger comprising: an integral wire having one end formed into a supporting hook, the other end constituting a shoulder supporting arm having its free end formed into a loop to be slipped over said hook, the portion adjacent said hook constituting another shoulder supporting arm, the portion between said arms constituting a horizontal trouser support; and a moth ball container carried by each shoulder arm, said container consisting of an open helical coil of resilient wire, and a conical end closure at one end consisting of coils of the same wire disposed in a spiral of diminishing diameter.

25 9. A garment hanger comprising: an integral wire having one end formed into a supporting hook, the other end constituting a shoulder supporting arm having its free end formed into a loop to be slipped over said hook, the portion adjacent said hook constituting another shoulder supporting arm, the portion between said arms constituting a horizontal trouser support; and a moth ball container carried by each shoulder arm, said container consisting of an open helical coil of resilient wire, and a conical end closure at one end consisting of coils of the same wire disposed in a spiral of diminishing diameter.

30 10. A garment hanger comprising: a longitudinally curved shoulder supporting plate having an aperture disposed centrally thereof, a moth ball container consisting of an open helical coil of resilient wire disposed immediately below said plate, a wire disposed interiorly of said container, an integral lug at each end of said plate bent over the ends of said wire to hold the hanger in proper assembly and a hook passing through said aperture and integral with said last named wire.

35 11. A garment hanger comprising: a longitudinally curved shoulder supporting plate, a moth ball container consisting of an open helical coil of resilient wire disposed immediately below said plate, a wire disposed interiorly of said container, an integral lug at each end of said plate bent over the ends of said wire to hold the hanger in proper assembly and a hook passing through said aperture and integral with said last named wire.

40 12. A garment hanger comprising: a longitudinally curved shoulder supporting plate having an aperture disposed centrally thereof, a moth ball container consisting of an open helical coil of resilient wire, and a conical end closure at one end consisting of coils of the same wire disposed in a spiral of diminishing diameter.

45 13. A garment hanger comprising: a longitudinally curved shoulder supporting plate having an aperture disposed centrally thereof, a moth ball container consisting of an open helical coil of resilient wire, and a conical end closure at one end consisting of coils of the same wire disposed in a spiral of diminishing diameter.

50 14. A garment hanger comprising: a longitudinally curved shoulder supporting plate having an aperture disposed centrally thereof, a moth ball container consisting of an open helical coil of resilient wire, and a conical end closure at one end consisting of coils of the same wire disposed in a spiral of diminishing diameter.

55 15. A garment hanger comprising: a longitudinally curved shoulder supporting plate having an aperture disposed centrally thereof, a moth ball container consisting of an open helical coil of resilient wire, and a conical end closure at one end consisting of coils of the same wire disposed in a spiral of diminishing diameter.

60 16. A garment hanger comprising: a longitudinally curved shoulder supporting plate, a moth ball container consisting of an open helical coil of resilient wire disposed immediately below said plate, a wire disposed interiorly of said container, an integral lug at each end of said plate bent over the ends of said wire to hold the hanger in proper assembly and a hook passing through said aperture and integral with said last named wire.

65 17. A garment hanger comprising: a longitudinally curved shoulder supporting plate, a moth ball container consisting of an open helical coil of resilient wire disposed immediately below said plate, a wire disposed interiorly of said container, an integral lug at each end of said plate bent over the ends of said wire to hold the hanger in proper assembly and a hook.

moth ball container, the combination of a moth ball container consisting of an open helical coil of resilient wire, a wire disposed interiorly of said coil and projecting from its ends, and a cover plate disposed over said container and having integral lugs cooperating with the ends of said wire to hold the hanger in assembled relation.

15. A garment hanger comprising a single wire looped in shouldered form, one end of said wire terminating in a suspension hook and the other end terminating in an engaging hook, an apertured garment rest superimposed over the shoulders of said wire, said rest having terminal tongues for clamping the shouldered ends of the wire, and a spring coiled around each shoulder for holding disinfectants and insect repellents.

16. A garment hanger comprising a wire bent in shouldered form, one end of said wire terminating in a suspending hook and the other end of said wire being affixed to the bottom portion of said suspending hook, vermiciformed springs coiled around the shoulders of said wire for holding disinfectants and insect repellents, and a garment rest superimposed over said coiled means, said rest having terminal tongues which are firmly engaged with the ends of said wire shoulders.

In testimony whereof I have affixed my signature to this specification.

PHILIP SINITZER.
